UNITED STATES PATENT OFFICE.

MARTIN AUGUST SEAHOLM, OF CHICAGO, ILLINOIS.

PUMP AND MOTOR.

Application filed December 9, 1926. Serial No. 153,524.

My invention relates to a machine of the rotary piston type which may be used either as a pumping engine, or as a motor, and is reversible in direction of rotation. In my 5 pending application for patent filed December 9, 1925, Serial No. 74,264, I have described a simple and efficient engine of this type, and my present invention may be regarded as a modification of the construction 10 therein disclosed, and having certain novel and desirable features of construction and advantages which will be apparent from the description hereinafter given, among which may be mentioned that of providing for a 15 more regular and uniform delivery of fluid by the engine when functioning as a liquid pump or as a blower directly connected to a nozzle. My invention resides in the novel construction and arrangement of the different 20 members and parts of the engine relating to the desirable features and advantages mentioned, the essential elements thereof being more particularly pointed out in the appended claims.

25 In the drawings, Figure 1 is a plan view of a preferred form of my invention; Fig. 2 is a side elevation of the same; Fig. 3 is a left end elevation of the same; Fig. 4 is a vertical section in a plane extending axially 30 of the rotor and working chamber of the engine; Figs. 5 and 6 are vertical cross-sections in planes indicated by the dotted lines 5—5 and 6—6, respectively, of Figure 4, viewed in the direction of the arrows; Figure 7 is a 35 vertical cross-section in a plane indicated by the dotted line 7—7 of Fig. 4, looking in the opposite direction, as indicated by the arrow; Fig. 8 is an axial vertical section of a modified form of my invention; Figs. 9 40 and 10 are views corresponding to Fig. 5, but severally showing modified arrangements of the sliding vanes carried by the rotor member; and Fig. 11 is an axial vertical section of another modified form of my 45 invention.

Similar reference characters indicate similar parts in all the figures of the drawings.

In the preferred form of my invention illustrated in Figs. 1 to 7 inclusive, I have 50 illustrated a double pump which is particularly adapted for the purpose of supplying a blast of air and a supply of fuel oil to fuel oil burners such as are now largely coming into use for heating purposes, though it 55 will be understood that my invention may be applied to single pumps or motors, ca-

pable of various other uses. Describing now the particular construction shown in the figures referred to, the casing, which may most conveniently be constructed of metal castings, includes a base 1 integral with an annular body member 1^a arranged to receive parts of the blower mechanism, a front cover member or cap plate 2, an intermediate body member 3 formed with a rearward 60 tubular extension 3^a, and a rear casing member 4 constituting a rear end cap housing parts belonging to the oil pump. The main body member is formed with a cylindrical inner face, and the cap plate 2 and intermediate body member 3 bolted to the main member are respectively formed with parallel side faces marked 8 and 8^a to make a smooth working fit with what will be termed the end faces of a cylindrical sleeve structure consisting of a ring or sleeve member 5 and with the side faces of a pair of vanes 6—6^a which slidably reciprocate in a slide-way extending diametrically through a core or rotor member 7, the vane 6 being pivoted 70 to the ring and the two vanes being stressed apart by a spring 100. The rotor member, for convenience of manufacture, is preferably formed in two parts, marked *a* and *b*, firmly secured together and separable in the 75 plane of the joint between side face of the cap plate 2 and the main body member. The part *a* is rotatably seated in a socket in said cap plate and is formed with a journal 9 mounted in a packed bearing forming part 80 of such cap plate or cover member, and the part *b* is formed with a cylindrical extension 9^a which is journaled in the body member 3 and its tubular extension 3^a, and which itself constitutes the rotor member of the smaller, 85 or oil pump within the rear casing member 4. A packing ring 10 is preferably employed around the extension 9^a to prevent leakage between the two pump structures.

It will readily be understood that the 100 metal pieces of which the parts *a* and *b* are formed may be fitted together at a ground joint, and the slideways for the blower and oil pump conveniently formed in the part *b* when it is separated, and that the parts may 105 be finished as one after they have been firmly secured together.

As illustrated, the body member of the casing is provided with two flow connections 11 and 12 on opposite sides of the center of 110 the machine having vertical passages communicating with horizontal cross passages

13 and 14, respectively, in such body member. The cross passage 13 communicates at its opposite ends with a pair of opposite duplicate recesses 15 and 15^a formed respectively in the cap plate 2 and intermediate body member 3, which recesses have inner arc-shaped portions, marked respectively 16 and 16^a, constituting ports which communicate laterally through duplicate curved and 10 tapering port openings (defined by the peripheral face of the core or rotor and end faces of the sleeve and the ends of the recesses) with the lune shaped space between the rotor and the sleeve and the faces 8 and 15 8^a of the cap plate and intermediate body member.

The cross passage 14 communicates in a similar manner with the recesses 17 and 17^a having current portions 18 and 18^a extending 20 in a direction opposite to that of the above mentioned recess portions 15 and 15^a and terminating in ports or port openings similar to and opposite port openings of the ports 16 and 16^a. As shown in the drawing, the 25 ports on one side of the pump extend from points near the line of contact of the sleeve and rotor to extreme ends which are diametrically opposite the extreme end of the ports on the other side.

30 The space between the ring and rotor and the casing walls intermediate the extreme ends of the ports constitutes the working chamber traversed by the vanes mounted in the rotor.

35 The oil pump operates in the same manner as the blower above described, though somewhat differently constructed. The core or rotor consists of the end of the cylindrical extension 9^a of the blower, which is slotted 40 to receive the vane members 19 and 19^a, the former pivoted to the ring 20 of the oil pump and the latter stressed apart from the former by a spring 21. It may here be explained, however, that in rapid operation of 45 the engine the centrifugal force of the vanes is sufficient to keep the vane 19^a in contact with the ring, so that the spring is not indispensable, and the same is true with respect to the vane 6^a of the blower. As before mentioned, the ring or sleeve 20 is rotatably mounted in the end cap plate 4 secured to the tubular extension 3^a of the intermediate body member.

The intermediate member 3 of the casing 55 is formed with flow connections 22 and 23 which, through passages in such member and opposite arcuate parts 24 and 25, communicate with the lune-shaped space between the rotor and sleeve 20, the ports and flow passages in, the oil pump opening at one end of the ring only, and not being duplicated on opposite sides, as in the case of the blower.

60 The operation of my novel pump will be readily understood from the foregoing description of its construction. Assuming that

the flow connection 12 is connected to a jet nozzle through which air is to be forced and that the rotor shaft is connected to a motor to drive the rotor in a counter-clockwise direction, as viewed in Figure 5, the vane 6^a 70 will force the air ahead of it out through the port 18 until said vane passes the lower end of said port and the vane 6 cuts off communication between the cylinder space and the inlet port 16, after which the last mentioned vane will in its turn force the air ahead of it through an arc of 180°, while the vane 6^a is also moving through an arc of 180° and passing idly first through the stream of air passing through the port 18 and then 80 through the incoming stream of air drawn in back of the vane 6 through the port 16. It is manifest that the alternate working strokes of the vanes 6 and 6^a will each begin with a substantial volume of delivery which 85 will first increase somewhat and then decrease through the arc covered by the stroke, but will not vary greatly. I therefore attain a much greater regularity of flow than in the pump described in my former application above mentioned, in which a single vane working through substantially an entire circle is employed, and the flow rises 90 from zero to maximum through a half revolution of the rotor, and falls from maximum to zero through the other half revolution. The volume of delivery is also greater with a pump of the same dimensions. 95

It will be understood that the vanes 19 and 19^a of the oil pump act in the same manner as the vanes of the blower to force oil within the cylinder space out through the flow connection 23, and draw oil in through the connection 22. It will be noted, also, that the vanes of the blower and the vanes 100 of the air pump are arranged at right angles to each other, whereby a minimum variation in load upon the source of power is attained. 105

In Figure 9 I have illustrated a modified form of my invention which, in addition to 110 a pivoted vane, marked 26 and a vane aligned therewith, I employ two additional outwardly spring-pressed vanes 28 and 28^a, arranged in radial slots in the rotor. In this form of my invention the inlet ports 115 29 and outlet ports 30 (one only of each being shown) extend through arcs of approximately 135°, so that between the extreme ends of the ports the working chamber of the cylinder space extends through 120 an angle of about 90°, thus still further reducing the amount of pulsation of flow, and slightly increasing the delivery of a pump of a given size of rotor and ring.

In Figure 10 I have shown a further 125 modification in which I employ three vanes, one vane 31 extending clear through the diametrical slot in the rotor and pivoted at one end to the ring or sleeve and two auxiliary spring-pressed vanes 32 and 33 approxi- 130

mately 120° distant from the pivoted end of the vane 31, the inlet ports 34 and outlet ports 35 extending through angles of 120° each upon each side of the contact point between the rotor and ring thus providing a working chamber extending through an angle of approximately 120° .

In Figure 8 I have illustrated a single pump embodying my invention in which the extended end of the rotor 36 is formed with peripheral gear teeth 37 arranged to mesh with a pinion 38 also housed within the casing and mounted on a packed power shaft 39, the construction in other respects resembling that illustrated in Figure 4. The power shaft 39 may be the motor shaft of an electric motor, the reduction in gearing afforded by the pinion 38 and gear teeth 37 rendering the machine well adapted for the pumping of liquids.

In Figure 11 I have illustrated a modified form of my invention (the specific construction of which is not claimed in and by the present application), in which the sleeve structure includes two sleeve members or rings marked 40 and 41, each equipped with a pivoted vane 42 and cooperating with a diametrically opposite auxiliary vane 43, are mounted in a common ring seat, the vanes all working in a single diametrical slot in the rotor extending axially the entire width of the ring seat. It is obvious that while the vanes remain at all times in alignment in a common plane each pair of vanes 42 and 43 with its associated ring will rotate as a separate unit. One ring and its vanes will be accelerating while the other is slowing down, and vice versa, and the vibration tending to develop from the change of speed of the one will therefore be neutralized by the other.

As in my prior application above mentioned, the pivotal connection of the blades to the sleeve serves to positively actuate the latter, and the inner face of the sleeve provides a peripheral wall for the working chamber which travels in the same direction as the rotor and vanes at the same angular velocity. The auxiliary vanes, while they may be spring-pressed against the sleeve, have very little tendency to wear, as the point of contact shifts but slightly. Moreover, the seat of the sleeve in the casing has no tendency to wear out of a true cylindrical shape, and the defect of irregular wear to which pumps employing a vane having a sliding contact directly upon a circular seat in the casing is thus entirely overcome.

It will be understood that my machine is completely symmetrical and will operate equally well in either direction of rotation. It will also be understood that by connecting either one of the two flow connections of either pumping unit to a source of fluid

under pressure, it will function as a motor and drive the power shaft. For instance the parts described as constituting the blower may be so connected to function as a compressed air or steam engine to drive the oil pump, or the parts described as constituting the oil pump may be connected to function as a water or other fluid motor to drive the blower.

I claim:

1. In a fluid pressure engine, a stationary closed casing; a ring rotatably mounted within said casing and having an internal cylindrical face, a rotor having a cylindrical face of lesser diameter than the internal face of the ring, said rotor having at one end at least a portion extending beyond the plane of the corresponding end of the ring and rotatably mounted in the casing and said rotor being mounted eccentrically within the ring and contacting its inner face, a plurality of vanes of the same width as said ring slidably mounted in said rotor, one of said vanes being pivoted to said ring and said casing being formed with inlet and outlet flow passages terminating severally in ports opening between said ring and rotor on opposite sides of their line of contact and the said vanes constituting pistons carried successively by said rotor into a working chamber between the ring, and rotor and the casing walls intermediate the extreme ends of said ports.

2. In a fluid pressure engine, a stationary closed casing, a ring rotatably mounted within said casing and having an internal cylindrical face, a rotor having a cylindrical face of lesser diameter than the internal face of the ring, said rotor having at one end at least a portion extending beyond the plane of the corresponding end of the ring and rotatably mounted in the casing and said rotor being mounted eccentrically within the ring and contacting its inner face, a pair of vanes of the same width as said ring slidably mounted in said rotor diametrically thereof, one of said vanes being pivoted to said ring and said casing being formed with inlet and outlet flow passages terminating severally in ports opening between said ring and rotor on opposite sides of their line of contact and said vanes constituting pistons carried successively by said rotor into a working chamber between the ring and rotor and the casing walls intermediate the extreme ends of said ports.

3. In a fluid pressure engine, a stationary closed casing, a ring rotatably mounted within said casing and having an internal cylindrical face, a rotor having a cylindrical face of lesser diameter than the internal face of the ring, said rotor having portions extending beyond the planes of the ends of the ring and journaled in bearing seats in the casing and said rotor being mounted ec-

centrically within the ring and contacting its inner face, a plurality of vanes of the same width as the ring slidingly mounted in said rotor, one of said vanes being pivoted to said ring and said casing being formed with inlet and outlet flow passages terminating severally in ports opening between said ring and rotor on opposite sides of their line of contact and said vanes constituting pistons carried successively by said rotor into a working chamber between the ring and rotor and casing walls intermediate the extreme ends of said ports.

4. In a fluid pressure engine according to claim 1, a casing including a main body member of the same width as the ring, and a pair of casing members secured to said body members on opposite sides thereof, at least one of said pair of casing members being formed with flow passages terminating at the port openings between the ring and rotor.

5. In a fluid pressure engine according to claim 3, a casing including a main body member of the same width as the ring, and a pair of casing members secured to said body members on opposite sides thereof, the body member being formed with flow connections and cross passages, and said pair of casing members being formed with registering opposite flow passages terminating at opposite port openings between the ring and rotor and also being formed with the bearing seats in which the rotor is journaled.

35 6. In a machine of the character set forth, a stationary cylindrical casing equipped with a removable cap-plate having its inner face provided with inlet and outlet ports, the body of said casing having inlet and outlet passages therethrough provided with orifices registering with the ports of said cap-plate, a rotary sleeve structure and a rotary core member journaled in said casing in eccentric relation and contacting with each other, and a vane pivotally connected with said sleeve member and slidable in a slot in

said core member, the ports in said cap-plate extending across the end surface of said sleeve member.

7. In a device of the character set forth, a casing comprising an open-ended annular body member formed with flow passages opening at one end of said body member, a cap-plate for said body member having its inner surface provided with ports registering with the flow passages opening at said end of such body member, an intermediate body member on the other end of said annular body member provided with a tubular extension equipped with inlet and outlet passages having port openings at the end surfaces of the tubular extension, a removable end-cap secured to said tubular extension and providing a cylindrical bearing, a sleeve journaled in said bearing, a sleeve journaled in said annular body member, a vane pivotally connected with each of said sleeves, a shaft having rotor members eccentrically located with respect to said sleeves and severally contacting therewith, said cores having slots receiving said vanes.

8. In a machine of the character set forth, a stationary cylindrical casing equipped with a removable cap-plate having its inner face provided with inlet and outlet ports, the body of said casing having inlet and outlet passages therethrough provided with orifices registering with the ports of said cap-plate, a rotary sleeve structure and a rotary core member slotted in a diametrical direction and mounted in said casing in eccentric relation and contacting with each other, and vane members including a vane pivotally connected with a sleeve member and also including a diametrically opposite vane slidable in the diametrical seat of said core member, the ports in said cap-plate extending across the end surface of said sleeve structure.

In testimony whereof, I have subscribed my name.

MARTIN AUGUST SEAHOLM.
